CLAIM

The ornamental design for a scooter as shown and described.

DESCRIPTION

FIG. 1 is a front and top perspective view of a scooter, showing our new design;

FIG. 2 is a front view thereof;

FIG. 3 is a rear view thereof;

FIG. 4 is a left side elevation view thereof;

FIG. 5 is a right side elevation view thereof;

FIG. 6 is a top plan view thereof; and,

FIG. 7 is an enlarged view of portion 7 shown in FIG. 1. The broken lines depict portions of the scooter in which the design is embodied that form no part of the claimed design.

1 Claim, 7 Drawing Sheets
